ATOMIZING STOPPER FOR LIQUIDS

Filed April 30, 1921

2 Sheets-Sheet 2

UNITED STATES PATENT OFFICE.

THOMAS J. HOLMES, OF BOSTON, MASSACHUSETTS.

ATOMIZING STOPPER FOR LIQUIDS.

Application filed April 30, 1921. Serial No. 465,892.

To all whom it may concern:

Be it known that I, THOMAS J. HOLMES, a citizen of the United States, and resident of Boston, in the county of Suffolk and State of Massachusetts, have invented certain new and useful Improvements in an Atomizing Stopper for Liquids, of which the following is a specification.

This invention has relation to the atomizers for producing fine liquid spray of the class which also serve as closures for liquid containers or bottles.

The invention has for its object the production of a simple and convenient atomizing stopper which, when adjusted for use, serves as a complete seal or closure to prevent leakage of the liquid contents from the bottle, and which by a very simple adjustment may be adapted to produce a liquid spray of any desired fineness. While the principal form of the invention herein shown is especially adapted for throat atomizers, the chief characteristic of which type as shown is a long delivery tube or nozzle capable of being inserted well into the throat when in use, yet it will be understood that the invention is capable of application to other forms of atomizers also.

Heretofore it has been proposed to construct a throat atomizer of this type with a rotatable plug having ports or passages through it adapted to register with passages in the stopper body on the principle of a gas cock, but it will be perceived that in such type of atomizers when the plug cock is turned the long tube for conveying the liquid to the nozzle remains filled with liquid which can leak out and do much damage to any articles packed with it in a trunk or traveling bag. It is characteristic of the present invention that when the adjustable atomizing tube is turned to closed position, no leakage of contents of the throat tube carrying the liquid is possible since it is sealed at the nozzle or outlet end.

Generally speaking, the invention comprises the combination of a stopper body provided with liquid-discharging and bottle-venting passages so arranged that an internally located compressed air tube is arranged, when shifted to closing position, to close the nozzle orifice and said passages in the stopper to completely seal the device against any possible leakage. This and other features of the invention will be de-

scribed in the following specification and will be defined in the claims hereto annexed.

In the accompanying drawings I have illustrated several different forms embodying the principles of this invention, in which:

Figure 1 is a central vertical section of a complete atomizer constructed in accordance with this invention of the type especially designed for spraying the throat.

Figure 2 is a detail view in cross section adjacent to the outlet nozzle.

Figure 3 is a central vertical section of a modified form of atomizing stopper adapted for use in spraying germicide or perfumery or the like.

Figure 4 shows a modified construction of throat atomizer in which the air bulb is connected to the body portion of the stopper instead of to the adjustable air tube member.

Figure 5 is a vertical section showing details of a modification.

In the practice of this invention according to the form shown in Figure 1, the stopper 2 is made with a hollow internally threaded cap 3 carrying a packing washer or gasket 4 and is adapted to be screwed upon the neck of a bottle 1 to form a stopper or closure therefor.

The head 5 or upper portion of the stopper is formed with a transverse bore 6 in which is secured, by solder or otherwise, a liquid-conducting tube 8 which forms a continuation of the liquid tube 19 which projects down toward the bottom of the bottle 1. This liquid discharging tube 8 is provided with a tapered outlet nozzle 9, through which the spray is delivered.

A compressed air pipe 13 has its rear end secured in a sleeve 12 which has screw threaded engagement at 10 with the interior of the liquid tube 8 so that the air-delivering member is adjusted longitudinally as it is turned in its screw threaded bearing. The sleeve has a knurled head 18 to facilitate its rotation by hand.

It will be observed that at its rear end the transverse bore 6 of the head 5 is tapered or flared to fit a corresponding taper 7 formed on the sleeve 12. It will also be noticed that at the delivery end the compressed air member or tube 13 is provided with a taper corresponding with the interior taper of the nozzle 14. These two tapered portions of the air tube are accurately spaced so that

both will come into close contact simultaneously with the opposed tapered seats formed in the fixed portion of the atomizer or stopper.

- 5 A nozzle guide washer 15 may be inserted close to the nozzle to form a guide for the long internal tube 13, and is provided with one or more openings 16 to freely admit the liquid to the discharge or spray nozzle.
- 10 An air-admitting duct 20 leads in the tapered seat 7 at the rear end of the transverse bore to the interior of the bottle so as to form a bottle-venting passage when the atomizer is open for use. It will be seen that 15 this passage is closely sealed when the internally adjustable spray member is screwed tightly against its abutting tapered seat. At the same time all exit or escape of the liquid from the tube 8 through the nozzle is 20 prevented by a similar close contact between the tapered surfaces at the nozzle end. Hence the device is completely sealed when the interior adjustable member is screwed up tightly against the stopper. An air-com- 25 pressing bulb 21 secured to the rear end of the sleeve 12 affords compressed air for atomizing purposes.

Figure 3 shows in vertical section a modified form of atomizer in which the fixed 30 "stopper" element 30 is provided with a downwardly extending cylindrical neck 31, bored to receive an eduction tube 39 in its lower end and having communication adjacent to the discharge nozzle orifice 34 at its 35 upper end to allow the liquid to flow through the nozzle when the tapered plug 37 is partly unscrewed to uncover this discharge duct.

The head or body portion 33 of the stopper is formed with a transverse internally 40 screw threaded bore or passage which is formed with a conical surface adjacent to the discharge orifice 34 of the nozzle. An adjustable threaded plug 37 fits into this transverse passage of the head and its conical 45 end seats snugly against the conical or tapered seat of the passage, as shown at 35, to seal the liquid discharge passage against communication with the nozzle.

An air-venting passage 40 leads from the 50 bottom of the neck 31 out through an enlarged conical seat 36 formed in the head 33 which is snugly engaged by a corresponding conical shoulder formed on the screw plug valve 37.

The plug 37 is provided with a longitudinal 55 passage or air duct 38 through which air may be forced by means of the compression bulb 42. Air is supplied from the exterior to the interior of the bulb by the diagonal 60 passage or inlet duct 41 closed by a check valve 42 to prevent escape of air from the bulb in the reverse direction when the bulb is compressed. A cork bushing 32 serves to make a tight joint between the stopper and the bottle neck in which it is inserted.

In the form of atomizer shown in Figure 4, instead of making provision for attaching the air-compressing bulb directly to the axially adjustable air tube, provision is made for attaching the bulb to the fixed or body 70 member of the stopper through which the air is forced in to the central axial adjustable tube member.

In this form of the invention the bottle 1 has its neck closed by the stopper 50 by a 75 screw cap engagement as in the form shown in Figure 1. The upward extension or head 51 of the stopper body is transversely bored, and has secured in the bore a lateral tubular extension 52 forming a conduit for the liquid which is delivered through the nozzle or spray cap 53 which in this instance is shown to have a screw-threaded connection with the tube 52 in order to secure axial adjustment thereof.

At its rear end the bored head 51 is provided with a tapered seat as shown at 61, and a similar tapered seat is formed on the intermediate rib or shoulder as shown at 65.

The stopper is provided with a liquid-discharge passage in the tube 66 which conducts the liquid through a port 67 in to the outer tube 52. A vent passage 62, when open, admits air from the outside to the interior of the bottle to maintain atmospheric pressure therein.

The stopper body is provided with a nipple 60 for the attachment of any suitable form of compressed air bulb, and is formed with an air-conducting passage 59 leading to the screw-threaded portion of the bore in the head 51 between the two tapered valve seats 61, 65.

The inner tube 55 is secured in the screw-threaded plug or sleeve 54 having tapered 105 surfaces properly arranged to abut against the tapered seats 61, 65, respectively. The rear end of the inner tube 55 is plugged or closed as shown at 63. The threaded connection at 58 between the adjustable compressed air tube and the interior of the transverse bore in the stopper serves to effect an axial adjustment either for the purpose of opening the passages 66 and 62 communicating with the interior of the bottle or for closing them when the atomizer is not in use.

The delivery end of the adjustable air tube or compressed air member is formed with a taper as shown at 56 corresponding with the inside taper of the opposite portion of the spray nozzle cap. This permits an independent adjustment between the spray nozzle cap and the air tube 55 so as to prevent leakage through the nozzle as in the case of the forms illustrated in Figures 1 115 and 3.

It will be observed that after using the atomizer with the inner tube member adjusted to give the desired fineness of spray, said inner tube member may be tightly 125

screwed against the seats provided in the corresponding portions of the stopper body or fixed member of the stopper, and that in such case no leakage will occur even if 5 the bottle be inverted through the air-venting and liquid discharge passages. Furthermore, in any form of the invention, if after closing or sealing the stopper in the manner indicated there still remains a few 10 drops of liquid in the open end of the nozzle, they can be completely removed by a single squeezing of the air bulb so as to leave the nozzle perfectly dry. The liquid contained in the long throat tube is sealed 15 at the discharge end so that no leakage is possible. It is, therefore, safe to pack the atomizer containing its liquid contents by screwing the inner spray member firmly 20 against the stopper and blowing out any moisture or condensation that may still remain in the spray nozzle.

The form of atomizer shown in Figure 5 utilizes the same principle embodied in Figure 4 of connecting the air compressing bulb with the stopper body instead of with the central compressed air tube as in Figure 1, but differs somewhat in detail of construction. In this form the stopper 25 has an air inlet passage 71 formed on the 30 arc of a circle to permit the use of a single curved pin which can be easily withdrawn from the die-cast stopper-body instead of using two angularly disposed pins to form this air passage as would be the case in the 35 form of Figure 4.

Moreover, the detachable screw plug 72 has only one tapered seat at 73 which engages a similar surface formed in the stopper body to close that end of the atomizer 40 and prevent leakage through the bottle-venting passage 74. The inner central compressed air tube 75 is connected by means of port 76 with the arc shaped air inlet passage 71, and is sealed at the outer end 45 of the internal tapered contact with the external tube 77 in the manner illustrated in Figure 1.

The screw plug is formed with a series 50 of stepped portions of different diameter each provided with a comparatively short section of screw thread so as to afford a longer screw-threaded engagement between the plug and the bored head as shown at 78, 79 and 80, while at the same time making 55 it necessary to give only a few turns to the screw to disengage it entirely from the internally screw threaded bore. At 81 this screw plug forms a cylindrical engagement with the surrounding wall of the 60 transverse bore in the stopper so as to assist in preventing leakage of the liquid from the tube 77 back into the air duct 71. The discharge of liquid from the bottle in the case of the form shown in Figure 5 is 65 through the liquid tubes 83 and 77.

What I claim is:

1. An atomizing stopper for bottles embracing in combination a stopper member adapted to form a closure for the bottle and provided with bottle-venting and liquid-discharge passages to afford communication between the exterior of the stopper and the interior of the bottle, and an axially adjustable spray-regulating member provided with an air duct for conveying compressed air to the spray nozzle at the discharge end of the liquid passage, said axially adjustable member operating by its axial movement to cut off communication between the interior of the bottle and the outer ports of said passages in its sealing position of adjustment and to open such communication when adjusted for atomizing liquid, substantially as described.

2. An atomizing stopper for bottles embracing a stopper member constructed to form a bottle closure and provided with a liquid conduit in communication with the interior of the bottle terminating in a spray delivery nozzle, said stopper having also a vent duct for admitting outside air into the interior of the bottle in combination with an adjustable compressed air tube formed to close the nozzle end of said liquid conduit against the escape of liquid and the outer end of said air vent duct, said adjustable compressed air tube being located inside said liquid conduit and nozzle, substantially as described.

3. An atomizing bottle stopper embracing a body member adapted to form a closure for a bottle, said body member being provided with liquid-conducting and air-venting passages in communication with the interior of the bottle, and having an elongated tubular extension provided with a nozzle for conducting liquid to the nozzle, and an axially adjustable compressed air tube mounted inside said tubular extension and adjustable axially therein for the purpose of cutting off the flow of liquid through the nozzle while permitting air to be discharged therethrough, substantially as described.

4. An atomizing bottle stopper embracing in combination a body member adapted to form a bottle closure and provided with a liquid-carrying tube and an air venting tube having communication with the interior of the bottle, an elongated liquid conveying throat spraying tube formed with a contracted delivery nozzle, and an interior axially adjustable compressed air tube arranged by its adjustment to close the throat spraying tube at its outlet end to prevent the escape of liquid, and means for closing an air-vent passage in said stopper when said liquid outlet is closed, substantially as described.

5. An atomizing bottle stopper embracing

a body member adapted to form a bottle closure and provided with an enlarged bore, an elongated tube mounted in said bore and terminating at its outer end in a spray delivery nozzle, an inner tube connected with a source of compressed air and having its outer end tapered to cut off the escape of liquid through the spray nozzle when axially adjusted, said compressed air tube being provided with a tapered valve surface arranged at its outer end to close a bottle-venting passage formed in the stopper, substantially as described.

6. An atomizing bottle stopper embracing in its construction a body member adapted to form a bottle closure, two concentric projecting tubes mounted in said stopper one inside the other and having their delivery ends formed to provide a closure to prevent the escape of liquid from the intermediate tubular space between said tubes, the inner tube having communication with a source of compressed air and being axially adjustable along the outer tube, guiding means interposed between the two tubes near their discharge ends, the outer tube having communication with the interior of the bottle in order to admit liquid therefrom for atomizing purposes, substantially as described.

7. An atomizer for liquids embracing in its construction a stopper body adapted to form a closure for a bottle, inner and outer elongated tubes supported by said body member, the latter tube being provided at its discharge end with a spray nozzle, and the inner tube being axially adjustable to close said nozzle against the escape of liquid, air-compressing means having communication with the inner tube to force compressed air therethrough whether the nozzle is open or closed for the discharge of liquid, said air-compressing tube being provided at its rear end with a valve surface for closing the bottle-venting duct formed in the stopper body, substantially as described.

8. An atomizer for spraying the throat or the like, embracing in its construction a body member adapted to form a bottle closure, an elongated liquid carrying tube secured in said stopper body and provided at its outer end with an adjustable nozzle, a compressed air tube mounted inside of said liquid carrying tube and having screw-threaded engagement with the stopper to secure axial adjustment, said compressed air tube being provided with a plurality of tapered valve surfaces formed to seat against cooperating surfaces of the bottle stopper member to close the passages therein in order to prevent the leakage of liquid from the bottle, substantially as described.

9. In an atomizing bottle stopper the combination of a stopper body provided with

bottle venting and compressed air passages, an elongated outer tube having communication with a liquid supply tube, an inner air conveying tube, an adjustable screw plug having threaded engagement with the stopper body and forming an adjusting support for said inner air tube, said outer and inner tubes and said screw plug and stopper respectively being provided with cooperating concentric surfaces to seal the device against leakage when screwed tightly together, substantially as described. 75

10. An atomizing stopper for bottles embracing in combination, a bottle-closure member provided with liquid-discharge and bottle-venting passages, and a tubular air-conducting member mounted interiorly of the outer portion of the liquid-discharge passage and having annular faces arranged to cut off communication between the outer ports of said passages when in one position of axial adjustment and to open external communication with the interior of the bottle when axially adjusted to atomizing position, substantially as described. 80

11. An atomizing bottle stopper embracing in combination a body member provided with a bottle-venting duct and having concentric tubes leading to a liquid discharge nozzle, the inner tube having axial adjustment to seal and unseal the outer ports of the bottle-venting duct and the outer tube which carries the liquid to the spray nozzle, and an annular washer secured to the inner tube so as to be interposed between the inner tube and the outer tube, substantially as described. 90

12. An atomizing bottle stopper provided with a liquid-conducting tube terminating in a spray nozzle and having communication with the interior of the bottle, a concentric axially adjustable air-supply tube mounted inside said liquid tube to supply air to said nozzle for atomizing the liquid, and an annular member secured to the inner tube with its periphery in contact with the interior wall of the outer tube whereby the annular member is withdrawn through the outer tube by the withdrawal of the inner tube, substantially as described. 100

13. An atomizing stopper for bottles and the like embracing a bottle-closure and liquid-delivery tube extending therewith and provided at its outer end with a spray nozzle, and an axially removable air-supply tube mounted inside said liquid tube and carrying a spacing washer on its exterior whereby the removal of the air-tube acts, through said washer, to clear out the liquid tube, substantially as described. 110

In witness whereof, I have subscribed the above specification.

THOMAS J. HOLMES.
